(57) **CLAIM**

The ornamental design for a rotatable campfire stick, as shown and described.

DESCRIPTION

FIG. 1 is an end view of a rotatable campfire stick in accordance with my new design;

FIG. 2 is a top view of the rotatable campfire stick;

FIG. 3 is a front view of the rotatable campfire stick;

FIG. 4 is an enlarged vertical sectional view taken along line 4—4 of FIG. 3; and,

FIG. 5 is an enlarged vertical sectional view taken along line 5—5 of FIG. 3.

The broken lines in FIGS. 1 through 3 represent unclaimed environmental subject matter.
